HAND LOOM

Vesta Conn Bennett, Northport, N. Y.

Application April 28, 1947, Serial No. 744,375

3 Claims. (Cl. 139—34)

1

This invention relates to improvements in looms and more particularly to that class known as hand-looms.

One object of this invention is to provide a neat, simple and inexpensive hand-loom which can be utilized for making rugs, afghans, mats or other articles.

A further object of this invention is to provide a convenient device for weaving by hand whereby a fabric may be produced without mechanical means for moving or reciprocating the heddles.

A further object of this invention is to provide a hand loom having a hand operated heddle of very simple construction which may be operated to depress alternate pairs of warp threads below the normal plane of the warp threads for forming the shed below the normal plane of the threads.

Another object of this invention comprises a new method of hand weaving in which the user strings the warp thread on a hand loom to form a square and then weaves the weft thread through each pair of warp threads, a row of cloth or nap ties are then affixed to the warp paired threads and the weft thread is again woven through the warp and pushed up tightly to bind against the cloth or nap ties, this is repeated until the square formed by the frame and the warp thread is covered with woven weft thread and tied naps.

A still further object of this invention is to provide a convenient device for a hand tied nap rug with a woven base that will not unravel and in which the nap will not pull out.

A further object of this invention is to provide a convenient device for rapid hand tying of a nap on a woven base inserting the hand tying in rows on the warp threads in pairs and tightly binding each row as it is completed.

Another object of this invention is to provide a convenient device on which the warp may be set up for weaving and on which a predetermined design may be laid out on the warp threads so that variations in color of the nap may be easily followed as they are tied thereon.

Further objects are to provide a construction that is simple, efficient, economical and easy to assemble and operate as will more fully appear by reference to the accompanying description and the drawings in which:

Fig. 1 is a perspective view of the hand-loom as set for stringing the warp thread,

Fig. 2 is a perspective view of the hand-loom with the warp thread strung and prepared for weaving the weft thread,

2

Fig. 3 is an elevational view of one part of the heddle,

Fig. 4 is an elevational view of the other part of the heddle,

Fig. 5 is a partial plan view illustrating the start of the weaving operation,

Fig. 6 is a plan view illustrating the method of tying the nap between each pair of weft threads,

Fig. 7 is a perspective view of the hand-loom in which a plurality of rows of tied nap have been affixed and compressed into their finished relationship, and

Fig. 8 is a perspective view of a single bar heddle.

Referring to Fig. 1 there is illustrated a frame 10 that may be formed in a single U-shaped member 11 or may be comprised of three members to form a head portion 12 and two side supporting members 14 and 15. At the opposite end of members 14 and 15 there are provided two slots 16 and 17. An end bar 18 of approximately the same dimensions as the end member 12 will be mounted across the members 14, 15 and may be affixed in position by a pair of bolts 20, 21 and may be securely mounted by thread wing nuts mounted on the bolts 20 and 21. A center cross bar 23 is provided and is likewise affixed to the members 14, 15 by a pair of bolts 24, 25, likewise threaded to receive wing nuts to permit securing the bar 23 to the arms 14, 15. The end member 12 is provided with a plurality of equally spaced L-shaped hook members 30. The end member 18 is likewise provided with a similar number of equally spaced curved hook members 31 and the cross bar 23 is provided with a plurality of equally spaced pins 32. Of course, the width of the members 12, 18 and 23 will determine the number of hooks 30, 31 and pins 32 to be utilized, but in each use of the frame there shall be an equal number of pins used on members 12, 18 and 23. The member 23 is utilized in the position illustrated in Fig. 1 to string the warp thread, but when the stringing operation is completed the member 23 is removed by detaching the bolts 24 and 25 and the member 23 is then inverted and positioned as illustrated in Fig. 2 over a pair of apertures 34, 35 and the bolts 24, 25 again inserted therethrough to retain member 23 in the new position.

Referring to Fig. 2, member 12 is provided with a pair of cuts 36, 37 in which a pair of eye screws 38, 39 are mounted and member 23 is also provided with a pair of eye screws 40, 41. There are a pair of rods 42, 43 of appropriate length

mounted so that rod 42 passes through the eye bolts 38, 40 and rod 43 passes through eye bolts 39, 41. The rods 42, 43 may be locked in position by a pair of end pins 44, 45 mounted in member 12. Further apparatus necessary to construct an article on the hand-loom illustrated in Figs. 1 and 2, comprise a shuttle needle 47 and weight 48, Figs. 5 and 7, and a pair of wire heddles 49 and 50, Figs. 3 and 4. Another form of heddle 51 is illustrated in Fig. 8. When the heddle 51 is utilized it will be mounted similar to either member 49 or 50 that is, the eye screws at each end of the heddle 51 are used to support the heddle on rods 42 and 43 and thus the heddle may be used as a pusher bar.

Referring to Fig. 2, the manner of mounting the heddles 49, 50 will be apparent. (In this case alternate groups of four threads have the wire loop 49 passed over them, likewise the remaining groups of four threads each have the wire loop 50 passed over them.)

Referring to Fig. 1, the manner of utilizing this device may be followed by tying the end of a warp thread 53 to the first hook 30 of the head member 12. The thread 53 is passed around the first pin 32 of the member 23 and brought back and around the second pin 32 of the member 23 and thus repeated until the thread reaches the last hook 30 of member 12, where it may be tied. In order that the warp thread may be retained as described, a second thread 54 is tied to a first hook 31 of the member 13 and passed through the loop of the thread 53 about the first pin 32 of member 23 and back around the second hook 31 of member 13 and back through the loop in thread 53 around the second pin 32 and back around the next hook 31 and so repeated until it reaches the last hook 31 of member 13 where it may be tied. Thus, with the warp threads held in this relationship member 23 may be removed by detaching bolts 24 and 25 and twisting member 23 slightly and dropping downward through the frame. Member 23 is then reversed and mounted in the position illustrated in Fig. 2. The next step is to mount rods 42, 43 by passing rod 42 through eye screws 38, 40 and rod 43 through eye screws 39, 41 and locking them with the pins 44, 45. Pins 44 and 45 must be mounted through apertures in the end of rods 42 and 43. These pins may be similar to a cotterpin acting as a stop to prevent the rods from pulling out of the eyescrews 38 and 40. A pair of heddles 49, 50 are next positioned, as illustrated in Fig. 2. In this particular application the heddles have been formed, as illustrated in Figs. 3 and 4, to segregate groupings of four strings. This is to allow the warp threads to be depressed in groups of four during the weaving of the woof or weft thread. It will be noticed that for each group of threads that the member 49 may be threaded under the member 50 will be threaded over the same group and vice versa, the threads that 49 are threaded over member 50 will be threaded under. Thus, by depressing either 49 or 50, the heddle will depress alternate groups of threads to permit weaving the weft therethrough and members 49 and 50 are used alternately to form each shed of the weft thread. The manner of securing the ends of members 49 and 50 may be accomplished in various manners, but in this instance the wire is simply sprung open at its end so that the rods 42 and 43 are mounted within the end portion of members 49 and 50, as illustrated in Figs. 2, 3 and 4. However, when a different type heddle is used, or in the event the end loops of the heddles 49, 50 are

too stiff to spring into place then rods 42, 43 may be removed and passed through these end loops to hold heddles 49, 50 in their respective positions. The heddles 49, 50 in use also assist the rods 42, 43 by stiffening them and preventing bowing.

It is to be noted that thread 53, Fig. 1, is provided with a long loose end 55. This end is tied to the weight 48. The opposite end 56 of the thread 53 may be threaded through the eye of the needle 47 and be connected to a ball of thread 57. The device is now ready for its weaving operation. Referring to Fig. 5, with the needle 47 threaded the thread 56 becomes the weft thread. The needle is passed over rod 42 and over the first four threads, then under the next four threads and so on. When the weft thread reaches the rod 43, the weight 48 and thread 55 is passed through the loop in the weft thread, this acts as a retention warp for the ends of the weft threads. The weft thread is again woven through the warp threads but the groups of four threads that it passed over are now passed under and vice versa for each alternate group as is the practise in weaving (the weaving may be about pairs of threads but the groups of four provide a stiffer backing for a rug). Each time the weft thread passes over or under rod 43 the weight 48 is passed through the loop of the weft thread and allowed to hang over the side thus the weft thread is pulled tightly to give a retaining warp for the edge of the woven material. Pulling the weft thread too tightly would bow the rods 42, 43. During this weaving operation a pair of heddles 49, 50 may be used to assist forming the shed and thus provide a quick and easy operation with the needle 47. Referring to Figs. 3 and 4, it is easy to follow the effect of depressing either 49 or 50 if we assume all threads 53 are in the same horizontal plane. When 49 is depressed the threads 53 over which it passes will be depressed below all other threads and thus provide a sufficient spacing between two layers of threads to pass the needle 47 and its attached pair of weft threads 56. Likewise, on the next operation by depressing 50 the threads 53 over which it passes will be depressed and the weaving operation of the needle 47 and threads 56 may be repeated. Each subsequent weaving operation requires the depression of the heddles 49—50 in alternate steps.

Referring to Fig. 6, we may note that after each weaving operation with the needle 47, the operator stops and hand ties a plurality of short strips of cloth, wool yarn, or other suitable material. The pairs of warp thread 53 were utilized in this figure as the means of supporting the ties, however, different groupings may be utilized. After one row of hand tied nap has been applied the operator should use the heddle 49, 50 to provide a shed and weave the next row (pair) of weft threads 56 therethrough. The heddle may then be used as a pusher applying its flat face to force the weft threads 56 to bear tightly against the base of the tied nap. The operation may be continued as illustrated in Fig. 7 until the weft threads reach the loop ends 60 in the warp thread 53 at which time the square of rug or similar article is ready to be removed. Before completing the weaving operation the warp threads may become very tight but the cross member 13 may be moved up slightly by loosening the wing nuts of bolts 20, 21 and moving them forward in the slots 16, 17 (Fig. 1) when enough slack is obtained the wing nuts are again tightened to hold member 13 steady for subsequent weaving.

The heddle 51 (Fig. 8) may be used instead of

the heddles 49, 50, but it will provide a shed for one grouping only and the alternate weft threads must be woven in place by the needle. The heddle 51 does provide a good pusher or beater member for pushing the weft threads into a good tight relationship.

Before removing the finished square from the frame a retention warp 61 (which may be a length of thread from the ball 57) must be passed through the loops 68 of the warp 53. The thread 54 may then be untied and pulled out, also rods 42, 43 may be withdrawn and the square of material can be lifted from the L-shaped hooks 30. The end of thread 56 is cut, although a short length is left, also retention warp 61 has two loose ends and the weighted thread 55 is cut leaving a loose end, before cutting thread 55 it should be pulled tightly to make the material edge straight and even. All of these loose ends may be woven into the rug base to provide a neat finished square. A plurality of these finished squares are joined by interlacing the edges of the woven base in a zigzag weave thus making a rug or covering of any desired size.

It is to be noted that when a plurality of squares are joined with the zigzag weave the whole rug will have equal strength. The method of hand tying permits many variations in color and design, also the length of ties or nap may be varied without departing from the spirit of this invention. The hand tying of nap with closely bound weft produces an even finish in which the base or joining seams cannot show through. One way of utilizing this device where a desired design is to be followed is to transfer the design to the warp threads before weaving and hand tying.

Having described the apparatus for making a woven article and the method of utilizing this apparatus, the invention includes all modifications and changes that may be apparent without departing from the spirit of this invention and the invention shall be limited only by the appended claims.

What is claimed is:

1. A portable hand-loom comprising a U-shaped frame with an adjustable end bar secured to the open end of the U-shaped frame, a cross bar that may be attached mid-way between the

two ends of the frame, a series of hooks on the top face of the base of the U-shaped frame, a similar series of hooks on the top face of the end bar and a series of pins of equal number to those on the base of the U-shaped frame on the top face of the cross bar, a warp thread between the hooks on the base member of said U-shaped frame and the pins on the cross bar, a warp retaining thread between the end loops of the warp thread on the cross bar and the hooks on the end bar.

2. In a device according to claim 1 in which said crossbar is positioned in a reversed relationship adjacent to the end bar, a pair of guide rods supported between the base member of said U-shaped frame and the inverted crossbar and positioned at either side of said frame, a retention warp and weight, means to string said weight and retention warp through each end loop of the weft threads adjacent to one of said guide rods with said retention warp in a parallel relationship to said guide rod.

3. A portable hand loom comprising a rectangular shaped frame, a removable crossbar that may be attached midway between the two ends of the frame, a series of warp retaining pins on the top face of each end member of the frame, a similar series of pins on the top face of the crossbar, a warp thread between the pins on the one end of the frame and the pins on the crossbar, a warp retaining thread between the end loops of the warp thread on the crossbar and the pins on the opposite end of said frame.
